Primary Examiner — Thomas Johannes*Assistant Examiner* — Catherine Posthauer(74) *Attorney, Agent, or Firm* — Alison B. Kessler; Theodore R. Furman**CLAIM**

The ornamental design for a bottle for dietary supplement, as shown and described.

DESCRIPTION

FIG. 1 is a left side plan view of a bottle for a dietary supplement, showing our new design;

FIG. 2 is a front side plan view thereof;

FIG. 3 is a right side plan view thereof;

FIG. 4 is a back side plan view thereof;

FIG. 5 is a top side plan view thereof; and,

FIG. 6 is a bottom side plan view thereof.

In the drawings, the broken lines are shown for the purpose of illustrating portions of the article and form no part of the claimed design.
